UNITED STATES PATENT OFFICE.

JOSEPH McGRATH, OF MANTENO, ILLINOIS.

MAIL-TRANSFERRING APPARATUS.

1,202,300.

Specification of Letters Patent. Patented Oct. 24, 1916.

Application filed September 14, 1915. Serial No. 50,681.

To all whom it may concern:

Be it known that I, JOSEPH McGRATH, citizen of the United States, residing at Manteno, in the county of Kankakee and State of Illinois, have invented certain new and useful Improvements in Mail-Transferring Apparatus, of which the following is a specification.

My invention relates to mail transferring apparatus and contemplates a novel construction, combination and arrangement of parts more particularly hereinafter described and specifically pointed out in the claims.

15 In the drawings annexed: Figure 1, is a top plan view of the apparatus, the railway mail car upon which the delivery means is mounted being shown in section; Fig. 2, is a view in side elevation of the receiving portion of the apparatus; Fig. 2^a, is a view in side elevation of the delivery means; Fig. 3, is a vertical longitudinal section taken through the receiving device illustrated in Fig. 2.

25 Like numerals of reference designate like or corresponding parts throughout the several views.

Referring now to the drawings by numerals, 1 designates the railway mail car, 2 as 30 an entirety the delivery means, and 3 as an entirety the receiving means.

The delivery means in its preferred embodiment may be said to consist of an arm or crane 4 pivoted as at 5 interiorly of the 35 mail car 1 and at one side of a door opening 6 formed therein. A casting 7 fastened as at 8 to the car 1 acts as a bearing support for the arm or crane 4 that the latter may be swung (as indicated by the dotted line in 40 Fig. 1) into and out of a position for operation. A spring 9 is mounted in such proximity to said arm or crane as to act as an abutment therefor whereby the stress and strain incident to mail transfer operations is 45 materially reduced and the shock partially if not wholly absorbed.

The outer extremity of the arm 4 is extended rearwardly and at a right angle as indicated at 10 to terminate in an enlargement 11 which, when taken in connection with said extension 10 may be said to constitute the stationary retaining jaw of the delivery means.

50 For reference hereinafter, the stationary retaining jaw is designated as an entirety by the numeral 12.

A movable jaw 13 pivoted as at 14 to the stationary jaw 12 is mounted to coact with the latter in supporting the mail matter in a position permitting delivery thereof. An 60 enlargement 15 (like the enlargement 11) is formed at the free end of the movable jaw to normally contact with said enlargement 11. A spring 16 arranged to embrace a pin 17 acts as a means whereby the jaws 12 and 13 are yieldingly maintained in 65 engaging proximity. Said pin 17 also affords a means whereby the mail bag support designated as an entirety by the numeral 18 is removably held to extend 70 from the crane or arm 4, during a delivery operation, in a substantially horizontal plane. Said support 18 comprises a shank 19 annularly grooved as indicated at 20, an enlargement 21 and an extension 22, the 75 latter having a slot or opening 23 formed therein whereby to receive the enlargements 11 and 15 of the coacting retaining jaws 12 and 13 hereinbefore described. A ring 24 is mounted on the shank 19 to fit the recess 80 20 therein, said ring having a mail bag (indicated by the dotted lines) detachably secured thereto.

In assembling the mail bag upon the arm or crane prior to a delivery thereof to the 85 stationary support or receiving means 3, the jaws 12 and 13 are separated against tension of the spring 16, enlargements 15 and 11 made to contact and to fit the opening 23 therefor at one end of the shank, the extension 22 of the shank fitting beneath the pin 17 to engage therewith and through such engagement maintain the support 18 in the position desired. In a delivery operation, the enlargement 21 of the support is to contact with the receiving means, and by reason of such contact, the jaws 12 and 13 will be 90 separated or spread and the mail bag with its support 18 released with respect to the arm or crane 4, said mail bag, when thus 100 released, being held until later removed by the receiving means 3.

Coming now to a description of the receiving means, 25 designates a substantially rectangular frame. That side of the frame 105 toward the mail car is open to permit passage of the delivery means therethrough. Guide plates 26, extending in divergent relation from a point midway the terminals of the frame act to direct the mail matter 110 to be delivered against bumpers 27 mounted in opposed relation and for vertical yielding

movement. Springs 28 normally maintain the bumpers 27 in an extended position, the mentioned springs abutting at one end the said bumpers and at their opposite end 5 abutment blocks 29 secured to a central cross beam 30 (of the channel beam type) forming a part of the receiving frame. One channel bar or beam 30 is located at the forward side of the frame and another at the rear side 10 thereof, the former, forward bar being divided intermediate its ends to provide a passage for the delivery means during a transfer operation.

In operation, the crane 4 is swung into 15 the position illustrated in Fig. 1 before the mail car 1 shall have approached the receiving means 3. With the mail bag suspended from the delivery means as hereinbefore pointed out, and the arm extended as 20 illustrated, it is evident that the enlargement 21 of the support 18 will contact with the guide plates 26 of the machine and the arm or crane 4 with the bumpers 27. As the bumpers yield the arm or crane will 25 pass the receiving means while the enlargement, by reason of its size, will so contact with the guide plates 26 as to cause the jaws 12 and 13 to separate against tension of spring 16 and the support 18 to be 30 grasped by the bumpers 27 that the mail matter delivered to the stationary support be securely held until subsequently removed.

From the foregoing, taken in connection 35 with the accompanying drawings it will be further noted that mail matter may be delivered regardless of the direction of travel of the mail car 1, that the plates 26 not only act as a guide for the delivered mail but also as a means precluding passage of the 40 support 18 beyond the receiving means, and that the bumpers 27 subsequent to passage of the arms 4 therebeyond, will immediately recede to grasp the shank of the support and in this manner hold the delivered mail 45 against casual displacement and until subsequently intentionally removed.

In reduction to practice, I have found that

the form of my invention, illustrated in the drawings and referred to in the above description, as the preferred embodiment, is 50 the most efficient and practical, yet realizing that the conditions concurrent with the adoption of my device will necessarily vary, I desire to emphasize the fact that various 55 minor changes in details of construction, proportion and arrangement of parts may be resorted to, when required, without sacrificing any of the advantages of my invention as defined in the appended claims.

Having thus fully described my invention, 60 what I claim as new and desire to secure by Letters Patent is:

1. In a mail transferring apparatus, a delivery crane, a mail bag supporting device comprising a shank having an extension, releasable means on the crane for engaging the extension to hold and retain the support in a horizontal position, an annular groove provided in the shank for receiving the ring of the mail sack, oppositely disposed 70 webs on the shank, and stationary receiving means adapted to be engaged by the webs to retain the support and the mail sack subsequent to the interchange.

2. In a mail delivery apparatus, a supporting crane movable into and out of a position for operation, a stationary jaw formed at the outer extremity of said crane, a movable jaw pivoted to said stationary jaw, spring means normally maintaining said 75 jaws in proximity, a support for the mail bag provided with an opening for the reception of said jaws, an extension formed on said support, and a retaining pin conjunctively utilizable as a means to engage with 80 said extension and maintain the support in a horizontal plane, and as a means to mount 85 said spring.

In testimony whereof I affix my signature in presence of two witnesses.

JOSEPH McGRATH.
